UNITED STATES PATENT OFFICE.

WILBER E. HARVEY, OF GLENSHAW, PENNSYLVANIA.

CONTROLLING PROPORTIONS OF PULVERIZED-FUEL MIXTURE.

1,348,561.

Specification of Letters Patent.

Patented Aug. 3, 1920.

Application filed March 7, 1919. Serial No. 281,287.

To all whom it may concern:

Be it known that I, WILBER E. HARVEY, residing at Glenshaw, in the county of Allegheny and State of Pennsylvania, a citizen 5 of the United States, have invented or discovered certain new and useful Improvements in Controlling Proportions of Pulverized-Fuel Mixture, of which improvement the following is a specification.

10 My invention has to do with the art of burning solid fuel, which, in a finely divided or pulverized state, is carried in suspension in a flowing stream of combustion-supporting gas. While applicable to the 15 burning of different kinds of pulverized combustible fuel my invention finds particular adaptability to the burning of coal dust suspended in air, and it is with reference to such particular use that I will describe it.

20 In using, as a fuel for burners in a manufacturing plant, coal dust suspended in a stream of air, the usual practice is to reduce the coal to a pulverized condition at a crushing station at or near the plant, and 25 to mix the pulverized coal with a continuously flowing stream of air under pressure. A main conduit for carrying the mixture of air and coal dust is extended to the parts of the plant at which it is desired to burn 30 the fuel, and for each burner or set of burners a portion of the mixture is abstracted from the main conduit and conducted to the burner by means of a branch conduit. The initial mixture is usually 35 formed with an excess of coal dust, that is to say, the mixture does not contain sufficient air to effect complete combustion of the coal, and accordingly additional air is supplied to each burner by means of a suitable 40 blast.

For abstracting, for a burner, a portion of the mixture from the main conduit, the inlet end of the branch conduit is usually provided with a valve. It will be 45 understood that such valve merely controls the amount of a given mixture that is permitted to flow through the branch conduit, or, in other words, that the valve does not have the effect of varying the relative proportions of the mixture fed to a burner. Considerable difficulty has been experienced 50 in the use of such controlling valves in branch conduits by reason of the fact that they so obstruct the passage of the branch conduit that coal dust deposits in the branch conduit and is frequently ejected in mass,

causing undesirable puffs in the flame, and, occasionally disastrous explosions.

The object of my invention is to provide means whereby variable relative proportions 60 of a mixture of a combustion-supporting gas and combustible particles may be abstracted from a main conduit and fed to a burner through a branch conduit having an unobstructed passageway. 65

In the accompanying sheets of drawings, which form part of my specification, I have illustrated the preferred embodiment of my invention. Figure 1 is an elevation of a plurality of furnaces, a main conduit, and 70 branch conduits extending from the main conduit to the furnaces; Fig. 2 a vertical sectional view taken on the line II—II, Fig. 1; Fig. 3 an enlarged view of a portion of the main conduit and the upper portion 75 of a branch conduit; Fig. 4 a sectional view taken on the line IV—IV, Fig. 3; and Fig. 5 a sectional view taken on the line V—V, Fig. 4.

Referring to the drawings, the main conduit 1 for carrying the mixture of coal dust and air is indicated as extending above a plurality of furnaces 2 which may be of any suitable construction and for any desired purpose, as for example, the heating 85 of steel or other metals. As is usual in installations for burning coal dust, the main duct 1 may be a closed circuit. Each furnace is illustrated as being equipped with two burners 3, which also may be of any 90 suitable type or construction. Extending from the main conduit 1 to each burner 3 there is an unobstructed conduit 4.

At the inlet end of each branch conduit I provide means whereby variable 95 amounts of coal dust may be abstracted from the main conduit without substantially varying the amount of air so abstracted, or in other words, means whereby variable relative quantities of coal dust and air may 100 be so abstracted. While various means may be used to such end, I preferably provide a funnel-like orifice-member 5 having an inlet opening 14, preferably of unvarying size, which member may be so turned, or 105 otherwise adjusted that the general plane of its inlet opening may lie at various angles to the line of flow through the main conduit.

Any suitable means may be provided for 110 turning the orifice member 5. In the illustrative embodiment of my invention a pin-

ion 6 is keyed to the member 5, and, meshing with such pinion, there is a second pinion 11 keyed to a rod 12 extending downwardly to within easy reach of a workman 5 in front of a furnace 2. The orifice member is rotatably mounted in a saddle 15 secured to the main conduit 1 by yokes 16. The lower end of the saddle is provided with a flange 17 to which there is attached, 10 as by means of bolts 18, a flange 19 of a valve casing 20, a suitable spacer 8 being interposed between the flanges 17 and 19 of such thickness as to permit rotation of the pinion 6. The casing 20 is provided 15 with a valve 21 for the purpose of entirely closing the branch conduit 4 when the burner attached to such conduit is not in use.

In operation, when it is desired to abstract the maximum amount or proportion of coal dust, the member 5 is turned to the position indicated in the drawing, the orifice 14 fully facing the line of flow, indicated by the arrow 22, through the main conduit. 20 When it is desired to diminish the amount of coal dust abstracted, the orifice member is turned either to the right or to the left an amount depending upon the diminished supply desired. It will be understood that, 25 when the orifice is set at an angle to the line of flow, a less proportion of coal dust will be received than when the orifice fully faces the line of flow, assuming, of course, that at the point of abstraction the relative 30 mixture of coal dust and air remains the same. Generally speaking, the ratio between the amount of coal dust abstracted by the orifice when fully facing the line of flow and when placed at an angle to such 35 line of flow is substantially the same as the ratio between the projections of the orifice on planes at right angles to the line of flow. Because of the pressure under which the air 40 flows, that is to say the static pressure as distinguished from the velocity pressure, the amount of air abstracted by the orifice will, 45 within the practical range of adjustment of the orifice be substantially the same when the orifice is placed at an angle to, as when 50 fully facing the line of flow. Accordingly, by adjusting the position of the orifice, the relative quantities of air and coal dust abstracted may be varied to meet requirements, and at the same time a strong flow of the 55 mixture through each unobstructed branch conduit may be maintained.

For two reasons the relative quantities of coal dust and air carried by the main conduit varies with the distance of the main 60 conduit from the point of initial mixture. In the first place a certain amount of the coal dust gradually settles to, and to a large extent remains upon, the bottom of the conduit. Such dust is periodically blown or 65 otherwise removed from the main conduit.

Secondly, the withdrawal of portions of the mixture through the branch conduit varies the relative proportion of air and coal dust, the proportion of coal dust usually being diminished. By providing means such as 70 shown herein, or its equivalent, for varying the relative quantities of coal dust and air abstracted from the main conduit, the character of the flame supported by the mixture taken from any point along the main 75 conduit may, independently of a supplemental blast, be controlled according to requirements. In other words by varying the relative quantities of coal dust and air abstracted, either a smoky carbonizing, or a 80 white oxidizing flame may be had regardless of the variation of the mixture in the main conduit.

According to the provisions of the patent statutes, I have described the principle and 85 operation of my invention together with the apparatus which I now consider to represent the best embodiment thereof. However, I desire to have it understood that, within the scope of the appended claims, my 90 invention may be practised by other forms of apparatus than that shown and described.

I claim as my invention:

1. The combination with a main conduit 95 for carrying a flowing stream of combustion-supporting gas having solid combustible particles suspended therein, a burner, and a branch conduit extending from said main conduit to said burner, of an orifice member for abstracting from the main conduit a portion of said stream of gas and particles and delivering said portion to said branch conduit, and means for rendering said orifice member effective to vary the relative quantities of said gas and particles 100 abstracted from the main conduit through the branch conduit.

2. The combination of a main conduit for carrying the flowing stream of combustion-supporting gas having solid particles suspended therein, a burner, a branch conduit extending from said main conduit to said burner, and means at the inlet end of said branch conduit for abstracting from the main conduit variable relative quantities of 110 said gas and particles.

3. The combination with a main conduit for carrying a flowing stream of combustion-supporting gas having solid particles suspended therein, a burner, and a branch conduit extending from said main conduit to said burner, of an orifice member in said main conduit and communicating with said branch conduit, and means for adjusting the general plane of the orifice of said member with respect to the longitudinal axis of said main conduit whereby variable relative quantities of said gas and particles may be abstracted from the main conduit through the branch conduit.

4. The combination of a main conduit for carrying a flowing stream of combustion-supporting gas having solid particles suspended therein, a burner, an unobstructed branch conduit extending from said main conduit to said burner, and means at the inlet end of said branch conduit for abstracting from the main conduit variable relative proportions of said gas and particles.
5. The combination with a main conduit for carrying a flowing stream of combustion-supporting gas having solid particles suspended therein, a burner, and a branch con-

duit extending from said main conduit to 15 said burner, of an orifice member in said main conduit and communicating with said branch conduit, and means for adjusting the general plane of the orifice of said member with respect to the longitudinal axis of said 20 main conduit.

In testimony whereof I have hereunto set my hand.

WILBER E. HARVEY.
